UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

RAILWAY-CAR-TRUCK CONSTRUCTION.

1,390,450.

Specification of Letters Patent. Patented Sept. 13, 1921.

Application filed April 25, 1921. Serial No. 464,114.

To all whom it may concern:

Be it known that I, JOHN A. LAMONT, a citizen of the United States, residing at Chicago, in the county of Cook and State of Illinois, have invented certain new and useful Improvements in Railway-Car-Truck Construction, of which the following is a specification.

This invention relates to railway car truck arrangements and more particularly to equalizing mechanism in connection with six-wheel car trucks.

One object of the invention is to provide a simple and improved arrangement where- 15 by shocks incident to the starting and stopping of railway cars are prevented from being taken by the equalizing mechanism.

Another object is to provide a simple and efficient equalizing mechanism for six-wheel 20 car trucks adapted to meet the various requirements for successful commercial operation.

These and other objects are accomplished by means of the arrangement disclosed on 25 the accompanying sheet of drawings in which—

Figure 1 is a fragmentary side elevation of a railway car truck embodying my invention; and,

Fig. 2 is a sectional view taken in the planes of the irregular line 2—2 of Fig. 1.

The various novel features of the invention will be apparent from the following description and drawings and will be particu- 35 larly pointed out in the appended claims.

Referring to the figures of the drawings, it will be noted that I have disclosed my invention in connection with a six-wheel car truck including a truck side frame 10 having 40 end pockets 11 (only one of which is shown), for the reception of journal boxes 12 and an intermediate pocket (not shown) for the reception of a middle journal box. The general arrangement of these parts is shown 45 in detail in one of my copending applica- tions Serial No. 433,412 filed December 27, 1920. In the general arrangement the loads are transmitted through transverse bolster members, equalizing levers, and then to the 50 intermediate and end journal boxes.

In the present case it will be noted that the transverse bolster member 13 is mounted within a pocket 14 in the side frame and that the bolster member is mounted directly 55 upon the associated equalizing lever 15.

It is desirous that the shocks incident to the starting and stopping of the car should not be taken by the equalizing mechanism, but on the other hand should be taken by the bolster members and the side frame in which they are mounted. For example, in the starting and stopping actions the bolster 13 will pass into engagement with the pocket side walls 16 and all shocks be taken at such points, while at the same time permitting the equalizing levers to take a longitudinal movement with respect to the side frame. To permit the equalizing levers 15 taking this longitudinal movement and not take any of the shocks mentioned, the outer ends of 60 the levers 15 are slidably mounted or mounted for translatory movement on the side frame. In this particular instance, the outer end of each of the equalizing levers 15 extend upwardly and terminates in laterally 65 extending shoe portions 17 within the side walls 18 of the side frame 10. These shoes 70 rest and slide upon hard steel wear plates 19 which are mounted on inwardly extending brackets 20 formed integrally with the 75 side frame. The shoes 17 preferably have their lower engaging faces convex in shape 80 to permit a given amount of rocking movement of the outer or fulcruming end of the lever incident to upward and downward 85 movement of the bolster members 13 within the side frame. In this same connection, the engaging faces of the shoes 17 and the wear plates 19 are practically in the same horizontal plane with the engaging surfaces of the 90 bolster member 13 and equalizing lever 15 so that the up and down movement of the transverse bolster members 13 will have little or no tendency to thrust the said bolster members into engagement with the side 95 wall 16 of the pocket 14. Any cramping however would be prevented as the result of the sliding movement of the shoes 17 of the equalizing lever on the side frame.

By means of this arrangement therefore, 100 it is apparent that whenever the car is started in one direction or the other, the equalizing lever will slide on the side frame and will not take any shocks incident to such starting and stopping actions but that said 105 shocks will be taken by the bolster member 13 and the side walls 16 of the pocket 14.

It is my intention to cover all modifications of the invention falling within the spirit and scope of the following claims. 110

I claim:

1. In a railway car truck, the combination of a side frame having a bolster pocket, an equalizing lever, and a bolster member mounted in said pocket and supported by said lever, one end of said lever being supported by said side frame and having translatory motion thereon to prevent shocks incident to starting and stopping of the car being taken by said lever.
2. In a railway car truck, the combination of a support, an equalizing lever, and a bolster operatively associated with such support and supported by said lever, one end of said lever being supported by said support and having a translatory motion thereon to prevent shocks incident to starting and stopping of the car being taken by said lever.
3. In a railway car truck, the combination of a side frame having a bracket, an equalizing lever slidably mounted on said bracket for permitting longitudinal movement of said equalizing lever with respect to said side frame to prevent shocks incident to

starting and stopping of the car being taken by said lever. 25

4. In a railway car truck, the combination of a side frame having spaced side walls, an equalizing lever terminating in a pair of shoes within the walls of said side frame 30 and being slidably mounted on said side frame to permit longitudinal movement of equalizing levers and prevent longitudinal operating shocks being taken by the latter.

5. In a railway car truck, the combination of a side frame having a bolster pocket and spaced side walls with inwardly extending brackets, an equalizing lever, and a bolster member mounted in said pocket and supported by said lever, one end of said 40 lever terminating in lateral extending shoes slidably mounted on said brackets to permit longitudinal movement of said equalizing lever to prevent said lever from taking longitudinal shocks incident to car operation. 45

Signed at Chicago, Illinois, this 18th day of April, 1921.

JOHN A. LAMONT.
